Primary Examiner — Rosemary K Tarcza*Assistant Examiner* — Alison M Ofstun(74) *Attorney, Agent, or Firm* — Stefan J. Kirchanski; Zuber Lawler & Del Duca LLP(57) **CLAIM**

The ornamental design for an LED lamp fan, as shown and described.

DESCRIPTION

FIG. 1 is a left perspective view of an LED lamp fan showing my new design;

FIG. 2 is a front view thereof;

FIG. 3 is a back view thereof;

FIG. 4 is a left side view thereof;

FIG. 5 is a right side view thereof;

FIG. 6 is a bottom view thereof;

FIG. 7 is a top view thereof;

FIG. 8 is a left perspective view of the LED lamp fan, shown in a position of use;

FIG. 9 is a left side view thereof;

FIG. 10 is a left perspective view of the LED lamp fan, shown in a second position of use; and,

FIG. 11 is a left side view of thereof.

The broken lines present in the drawings are included for the purpose of illustrating portions of the LED lamp fan which form no part of the claimed design.
